UNITED STATES PATENT OFFICE.

OSCAR J. LAISY, OF CLEVELAND, OHIO.

AIRSHIP.

1,311,237.

Specification of Letters Patent. Patented July 29, 1919.

Application filed May 25, 1916. Serial No. 99,720.

To all whom it may concern:

Be it known that I, OSCAR J. LAISY, a citizen of the United States, residing at Cleveland, in the county of Cuyahoga and State 5 of Ohio, have invented a certain new and useful Improvement in Airships, of which the following is a full, clear, and exact description, reference being had to the accompanying drawings.

10 This invention relates to airships of a type wherein there is a gas bag provided with a frame on the interior for maintaining the shape of the bag, and the general object of the invention is to provide a simple efficient 15 construction of this interior frame so arranged that the bag may be folded close along the longitudinal shaft by the collapsing of the frame. This collapsing permits a convenient packing for shipment and 20 provides for easily erecting the balloon for inflation, as is fully set forth in my prior application No. 721,584, filed September 21, 1912.

Further objects of the invention are to 25 combine with such an airship of the dirigible type, one or more cars suspended beneath the same for carrying the driving mechanism, passengers etc., which may be conveniently attached to the balloon and be constructed 30 somewhat after the manner of an aeroplane so that the car may be detached from the balloon and carry with it its driving and propelling mechanism, allowing flight to be continued free from the supporting bag. Still 35 another object is to so arrange the car or cars, supported by the gas bag, that they may alight on water and be propelled along the surface of the same by the same propelling means used to cause the airship to 40 move through the air, when the cars are attached to the bag.

The above and other objects will become apparent in the following description which relates to the drawings, and the essential characteristics are hereinafter summarized in the claims.

In the drawings, Figure 1 is a side elevation of my airship with the cars attached; Fig. 2 is a transverse vertical section through 50 one of the cars showing the propelling means and the arrangement of the supporting planes, and manner of attaching the car to

the gas bag; Fig. 3 is a vertical transverse section through the entire airship showing one of the cars in rear elevation; Fig. 4 is a 55 sectional detail of the means for securing the spokes of the frame to the gas bag, and the manner of attaching the brace wires; Fig. 5 is a similar sectional detail taken at right angles to Fig. 4; Fig. 6 is a detail showing a 60 plan of the members at the outer side of the gas bag at the ends of the spokes illustrating the manner of attaching the bracing wires thereto; Fig. 7 is a longitudinal sectional detail, a portion of the frame holding the 65 gas bag distended, illustrating bracing means and the manner of dividing the balloon into compartments; Fig. 8 is a detail, being a transverse section showing the parts of the frame adjacent the shaft; Fig. 9 is a longitudinal sectional detail showing the means for securing the balloon at one end of the 70 shaft; Fig. 10 is a plan showing two cars adapted to be supported by the gas bag and provided with supporting wings of the aero- 75 plane type; Fig. 11 is a sectional detail of a modified construction of the securing means at the end of the spoke.

Referring to the drawings, my balloon is built with a central longitudinal lattice-work shaft 1, which is shown as formed of four longitudinal corner strips 2 of suitable light material, at right angles to which are cross braces 3 forming a box truss. This truss is braced and stiffened by diagonal 80 wires 4, tightly drawn between the joints of the longitudinal members and the cross braces. These wires preferably extend over metal saddle members 5 V-shaped in cross section and embracing the outer corners of 85 the strips 2 preventing the wire cutting into the wood or softer material of the strips, and the wires are preferably secured by staples indicated at 7, one leg of which may extend through the strips 2 and into the cross 90 braces 3. By this construction I provide a very light but strong and rigid shaft upon 95 which to construct an airship of this character.

Carried on this shaft is a series of trans- 100 verse rings indicated at 6, which in turn, carry members for pivotally securing the inner ends of the spokes 8 projecting radially from the shaft to the canvas 10 of the bal-

loon. Inside one or more of these rings 6 I may provide a plate forming a diaphragm indicated at 12, clamped between ends of the sections into which the shaft is preferably divided, the securing being effected by bolts indicated at 13, extending through the intermediate ring 6, and engaging rings 14 and 15 at either side thereof, which are in turn secured to the ends of the embraced section of the shaft by staples 16, (Figs. 7 and 8). Thus when these bolts are in position they may serve to tightly draw the sections of the shaft together onto the diaphragm, inside the intermediate ring 6, providing a shaft rigid from end to end of the balloon and divided by diaphragms preventing leakage from one compartment of the balloon into the other, as will be presently described.

The compartments are formed by transverse partition members made of canvas 17 and suitably braced by a web of wires shown at 21, and secured adjacent the shaft in a groove in the exterior of the ring 13 or 15 by wrapping wires 18, and sewed at their outer edges to the canvas 10 of the balloon as indicated at 19, near the ends of the adjacent set of spokes. In the form shown, the partition 17 at the right (Fig. 7) is laterally removed from the ring 6 by extending the ring 15, forming in effect, a sleeve embracing the lattice-work shaft. This prevents leakage from one compartment to the other while permitting me to provide short diagonal brace wires 20 extending from the ring or sleeve member 15 to a ring 22 shown as formed of angle-iron, extending around the shaft and spaced therefrom by radial members 24. The wires 20 preferably hold the ring 22 against lateral displacement to the left by reason of the spokes tending to fold in the opposite direction. The wires 20, which are shown as spaced apart (Fig. 8), may guide the spokes while they are being folded.

The spokes of the various sets which are shown as arranged in radial planes about the ring 6, are preferably braced by wires secured to the shaft adjacent the inner ends of one set of spokes and extending outwardly and slidably engaging the outer ends of the spokes of the next adjacent set, and then inwardly to the shaft. Such wires are indicated at 25, Fig. 7, and are shown as secured to eye-bolts 26 secured in the rings 14 and 15. The outer ends of the spokes are preferably provided with hollow sleeves in which may be carried pulleys 28, over which the wires 25 may run, as the spoke is folded toward or away from the shaft.

The brace wires 25 for the spokes may extend through the partition members 17 and by providing rubber diaphragms 30 clamped in openings in the canvas by rings 31 and having intermediate bosses through which the wires may pass, leakage through the

partition at these points is prevented by the close engagement of the rubber with the wires.

In order to compensate for the varying internal pressure of the gas, I prefer to provide internal air chambers into which air may be pumped or released as desired. Such air compartments may be formed by a longitudinal wall of canvas 35, sewed at each end to the cylindrical wall 10 and extending inwardly toward the shaft and then looped upwardly over the same, as indicated at 36, each air compartment being between two adjacent sets of spokes and having an end wall adjacent such spokes. It will be noted that by having the end walls of the sections of the air compartment divided and wrapped about the central shaft, that these air compartments will not interfere with the assembling of the canvas on the balloon frame, as the edges of the bag may be secured along one side while the end walls of the air compartments may be secured along their divisions, as indicated at 38.

In case two or more of these air compartments are provided in adjacent spaces between the spokes, communication may be used between such compartments by means of a tubular connection such as indicated at 39, joining the canvas forming the end walls.

In the form of air compartments just described, the inner longitudinal wall 35 may be looped around the shaft at its intermediate point, as shown, for example, at 37 in Fig. 7 forming a tubular portion embracing the shaft, the ends of which tubular portion may be secured to the rings adjacent the sets of spokes. By omitting this portion 37 looping around the shaft the top wall 35 of the air compartment may lie entirely under the shaft, being secured to the outer wall of the canvas and the entire bag may be passed over the shaft longitudinally, the spokes being previously folded closely along the same. To prevent the spokes and rings 22 interfering with passing the canvas longitudinally over the shaft I provide a comparatively large opening in one end of the canvas, and at the edge of this opening I secure an extension portion of canvas leading to the end of the shaft. This arrangement is illustrated in Fig. 9 in which the outer canvas 10 leads inwardly toward the end of the shaft but stops short thereof leaving a large opening from which a conical-shaped extension of canvas 43 may lead to the end of the shaft. The adjacent edges of the pieces 43 and main body of the canvas 10 are preferably secured by rings 44 which may be clamped together on the outwardly turned portions of the edges. By releasing these two rings 44, access may be had to the interior of the balloon, or, if the partitions 17 have separable seams so that they may pass across the rings 22, the entire bag, in-

cluding the partitions and the air compartment canvas, may be passed longitudinally off of the frame. To effect this, the spokes are folded and the canvas released from the 5 ends of the spokes and the partitions released from the rings 13 and 14.

The device for securing the spokes at their outer ends to the canvas preferably comprises a metal tubular member 40 embracing 10 a portion of the outer ends of the spoke and secured thereto, and carrying a pin 41 on which the pulley 28 may turn.

On the inside of the canvas 10, opposite the end of the spoke is provided a flat metal 15 plate 42, having downwardly turned ears 43 spaced apart, and adapted to stand on opposite sides of the outer portion of the tube 40. These ears are provided with openings adapted to receive the outwardly 20 turned ends 45 of a pivot member comprising a heavy wire substantially U-shaped, and having outwardly bowed portions 46 extending through openings in the side of the tube 40 whereby the portions 46 may be 25 pressed together withdrawing the members 45 from the ears 43. The plate portion 42 is secured to the canvas by screws extending through a corresponding plate 47 on the outer side thereof.

It is desirable to brace the outer ends of the several spokes by longitudinally and spirally extending wires between the ends of 30 spokes of adjacent sets, and this may be readily accomplished without interfering 35 with the folding movement of the spokes by providing a plate 50 inside of each plate 42 and having downwardly extending ears 52 through which the pivot members 45 may extend. Such brace wires, as above mentioned, 40 are indicated at 53, shown as secured to the edges of the clevis 50. A transverse pin 55 may extend across the upper end of the tube to prevent the wires 25 becoming disengaged from the ends of the spokes.

The spokes are intended to fold downwardly to the right in Fig. 7, which causes 45 the wires 25 to become slack. I prefer to take up this slack by elastic bands 49 connected to the intermediate portion of the 50 wire and to the rings 15 tending to draw the wire toward the same as the spokes are folded.

It is desirable to provide a net-work of 55 wires about the exterior of the balloon to reinforce the same against internal pressure. These wires preferably extend diagonally as indicated at 60 in Fig. 1. In constructing this net-work of wires, I prefer to make the same in a series of sections adapted 60 to be wrapped around the exterior of the balloon and have portions extend over buttons or knobs such as shown at 62 rigid with the outer plates 47 and be there secured by a washer-like member 64 embracing 65 the knob and held by a pin 65.

The balloon is preferably of the shape shown in Fig. 1 in which there are a number of sets of spokes of the same diameter, and adjacent the ends of the bag are sets of smaller spokes 8^a providing the tapering 70 of the bag toward each end. Accordingly, I arrange some of the rings to which the spokes are pivoted so that they may be slid along the shaft when the bag is folded, being drawn by the wires attaching the shorter 75 spokes 8^a to the ends of the longer spokes. This is shown in Fig. 9, where the ring 6^a is slideable on the inner ring member carrying the diaphragm 12 and to which are secured the rings 13 and 14 and the gas-tight 80 sleeves 75 and 37.

To accomplish this folding it is also necessary to have one end of the balloon attached to the shaft by a slideable ring 67 which may fold with the folding of the spokes and yet 85 which will not allow leakage, by reason of the portion 43 of the canvas being secured by wire wrapping 66. Attached at one end to the slideable ring 67, is a collapsible sleeve of canvas or like material 75, adapted to 90 prevent gas escaping at the connection between the shaft and ring 67. The ring 67 may slide with the folding of the spokes, but the adjacent ring 6 to which the sleeve 75 is connected is closed by the diaphragm 12 95 and connected with the end of the balloon by the sleeve, and thus this sliding is permitted while the leaking of gas is prevented when the balloon is being inflated. When the balloon is inflated the ring 67 is secured 100 to the end member 72 by the bolts 68.

The form of car which I prefer to use comprises a comparatively flat bottomed boat-like member 80 from each side of which rise lattice-work frame portions 82 secured 105 to the sides of the boat member 80, and secured at their upper ends by rigid extensions 84 connecting the frame members with the ends of adjacent spokes 8, as shown in Figs. 1 and 2.

Extending laterally from the frame members 82 and rigidly carried thereby is a transverse lattice-work beam member 85 carrying at each end a rotatable propeller 86, shown as driven by suitable flexible members 87, in turn driven by a suitable motor 88, mounted in the bottom of the boat-like car member 80. As shown, there are two of the boat-like members 80 connected by a lattice-work bridge, comprising two side members 89 and an intermediate narrow floor 90 which may be used for passengers to travel from one car 80 to the other. This intermediate bridge member between the cars is preferably detachable from the cars so that 120 when alighting upon the surface of the water, each car may propel itself by its own motor 88 and propellers 86 independently of the other upon being released from the gas bag.

Each of these cars may be provided with laterally projecting wings of the aéroplane type, as indicated at 92, extending from the lattice-work frame members 82 and braced by suitable wires 93. These laterally projecting wings may serve as supporting planes and used in conjunction with the propelling means. The car may be caused to rise and fly after the manner of an aéroplane, it being only necessary to provide stabilizing portions on these wings, and a suitable rudder carried in each car and adapted for attachment in operative position. Upon injury to the gas bag while flying, one or both of the cars or car may be detached therefrom, fly on more rapidly and support itself by these wings thus changing at once from the flying as a dirigible to the flying as an aéroplane.

At 95 I have indicated a rudder supported by the rear end of the longitudinal truss beneath the gas bag and operated by flexible members 96 to guide the airship when flying as the dirigible. A similar rudder may be provided at the opposite end of the balloon, if desired.

It is sometimes desirable to rotate the gas bag with relation to the car and this I may accomplish by passing around the balloon at several points trough-like members providing shives, indicated at 100 and secured to the ends of the spokes. Over each of these, I may pass a rope 102 which in turn extends through pulleys 103 carried by the frame work of the cars and by detaching the connecting members 84, and drawing these ropes which extend around the balloon at several points, the balloon may be rotated. This is particularly desirable when the car is secured to the ground to facilitate repairing the balloon at any point.

A further advantage of these ropes connecting the car with the balloon are that they may be used to entirely support the car or cars and by simultaneously cutting these ropes or withdrawing the pivots for the pulleys through which they pass, the aéroplane may be released from this supporting bag instantly allowing it to fly by itself while the bag, relieved of its weight, immediately rises free from the cars.

In Fig. 11, I have shown a modified construction of the device for securing the canvas to the spokes. In this case a tube at the end of the spoke, indicated at 110 is pivoted at 112 to a tubular member which is slidably embraced by a pair of flanged washers 114 between which is clamped the canvas 10. Also, clamped between these washers is a rubber member 115 adapted to slide along the spoke and make a gas tight connection therewith, and at the outer end of the tube 111 is a threaded flange 116 receiving a cap 118 which also embraces threads on the flange 119 of the outer washer 114.

Thus by releasing the cap 118 to which the net-work of wires 60 is secured, the canvas may be slid inwardly along the spokes to the inner end thereof. A pin 120, Figs. 7 and 8 may be removed to allow the removal of the spoke, when desired.

The latter feature is equally useful in the inflation of the balloon as the rubber member 115 prevents leakage of gas between the canvas and spokes, and the washers 114 and canvas may be pressed outwardly along the spokes as gas is forced into the bag until the canvas reaches the flange 116 whereupon the clamping is effected by the cap 118. A U-shaped wire 124 having outwardly flaring shoulders 125 and upturned ends 127 (Fig. 11) is carried in the tube 111 and serves as a latch preventing the inadvertent inward movement of this securing means when the cap is removed.

I may provide for anchoring the balloon in such a manner as to prevent injury by high winds by securing one end of the shaft to a suitable post or tower about which the balloon may swing when inflated. To this end I have shown straps 130 rigidly secured to the transverse member at each end of the balloon to which suitable ropes may be secured for thus anchoring the balloon.

Having thus described my invention, what I claim is:

1. In an airship, the combination of a gas bag, a frame for holding the gas bag distended, a plurality of boat-shaped cars arranged tandem detachably secured to said frame, a propeller and engine carried by each car and serving to propel the airship as a dirigible or propel each car by itself when detached.

2. In an airship, the combination of a gas bag, a frame for holding the gas bag distended, a plurality of boat-shaped cars detachably secured to said frame, propelling means carried by each car and serving to propel the airship as a dirigible or 110 propel the car by itself when detached, and a bridge extending between the cars and having its ends detachably connected thereto.

3. In an airship, the combination of a gas bag, a frame for holding the same distended, a car detachably secured to said frame beneath the gas bag and carrying a propelling means adapted to drive the car and gas bag as a dirigible balloon, said propelling means comprising a motor and laterally positioned propellers, means connecting the propellers and motor, and a transverse beam transversely carried by the car for carrying the propellers, and an aero- 125 plane support for the car.

4. In an airship, the combination of a gas bag, a frame for holding the same distended comprising a longitudinal shaft made in sections, members extending outwardly from 130

the shaft and secured to the canvas, canvas partitions transversely mounted in the gas bag and extending from the bag to the shaft, and bulk heads between the sections of the 5 shaft adjacent the partitions.

5. The combination of a longitudinal gas bag, of a frame for holding the same distended comprising lattice-work sections secured end to end, rings secured to the 10 lattice-work and secured together, a bulk head between said rings, a transverse canvas partition secured to one of said rings leading outwardly and secured to the canvas.

10. The combination of a longitudinal gas bag, of a frame for holding the same distended comprising lattice-work sections secured end to end, rings secured to the lattice-work and secured together, a bulk head between said rings, a transverse canvas partition secured to one of said rings leading outwardly and secured to the canvas, and a net-work of wires on one side of said canvas partition and adapted to brace the same.

15. The combination of a longitudinal gas bag, of a frame for holding the same distended comprising lattice-work sections secured end to end, rings secured to the lattice-work and secured together, a bulk head between said rings, a transverse canvas partition secured to one of said rings leading outwardly and secured to the canvas, and a net-work of wires on one side of said canvas partition and adapted to brace the same.

20. The combination of a gas bag, a lattice-work shaft extending longitudinally therethrough, spokes for holding the gas bag distended pivoted at their inner ends to the shaft and secured at their outer ends to the gas bag, brace wires leading from one set of spokes to the other and extending diagonally from points adjacent the shaft on one set of spokes to points adjacent the canvas at the other and slidably engaging the spokes.

25. The combination of a gas bag, a lattice-work shaft extending longitudinally therethrough, a series of rings carried by the shaft, sets of radiating spokes pivoted to said rings and secured at their outer ends to the gas bag, pulleys mounted in said spokes adjacent their ends, and brace wires leading diagonally from points adjacent the gas bag to points adjacent the shaft and over said pulleys thereby bracing the spokes

30. The combination of a gas bag, a lattice-work shaft extending longitudinally therethrough, a series of rings carried by the shaft, sets of radiating spokes pivoted to said rings and secured at their outer ends to the gas bag, brace wires leading from one set of spokes to the other and extending diagonally from points adjacent the shaft on one set of spokes to points adjacent the canvas at the other and slidably engaging the spokes.

35. The combination of a gas bag, a lattice-work shaft extending longitudinally therethrough, a series of rings carried by the shaft, sets of radiating spokes pivoted to said rings and secured at their outer ends to the gas bag, pulleys mounted in said spokes adjacent their ends, and brace wires leading diagonally from points adjacent the gas bag to points adjacent the shaft and over said pulleys thereby bracing the spokes

40. The combination of a gas bag, a lattice-work shaft extending longitudinally therethrough, a series of rings carried by the shaft, sets of radiating spokes pivoted to said rings and secured at their outer ends to the gas bag, brace wires leading diagonally from points adjacent the gas bag to points adjacent the shaft and over said pulleys thereby bracing the spokes while permitting them to fold along the shaft.

45. The combination of a gas bag, a lattice-work shaft extending longitudinally therethrough, a series of rings carried by the shaft, spokes pivoted to said rings and extending radially to the gas bag for holding the same distended and adapted to be folded along the shaft, concentric rings about the first mentioned rings positioned at one side of the spokes when the bag is distended and adapted to brace the same, parallel brace wires leading from said ring to the shaft at either side of said spokes whereby the spokes are braced and guided.

50. In an airship, the combination of a gas bag, a frame for holding the bag distended comprising a lattice-work shaft, sets of radiating spokes pivoted to the shaft and secured to the bag, brace wires leading diagonally from points adjacent one set of

spokes to the outer ends of the next adjacent set, a transverse canvas partition through said bag secured at the inner edge to the shaft and at its outer edge to the bag, said brace wires extending through said partitions, and rubber washers about said brace wires and secured in openings in said position. 70

11. The combination of a gas bag, a longitudinal lattice-work shaft extending therethrough, a series of members extending outwardly from the shaft to the bag for holding it distended, transverse partitions dividing said bag into compartments, two of said partitions being mounted adjacent each other and secured at their outer edges to the bag, rings about the shaft, the inner edges of the partitions secured to said rings, and a bulk head clamped between said rings and extending transversely of the shaft. 75

12. In an airship, the combination of a gas bag, a longitudinal shaft extending therethrough comprising lattice-work sections, rings secured around the ends of said sections, means for clamping said rings together forming a rigid shaft extending throughout the length of the bag, bulk heads clamped between the ends of said sections within said rings, members extending outwardly from the shaft to the canvas for holding it distended, and a partition dividing the bag into compartments having its inner edge secured to one of said rings and its outer edge secured to the bag. 90

13. The combination of a gas bag, a frame for holding the same distended comprising a longitudinal shaft, a plurality of sets of radiating spokes pivoted to the shaft and secured at their outer ends to the gas bag, some of said spokes being of different lengths, a bulk head positioned a short distance from one end of the shaft and extending through the shaft, a bulk head at the end of the shaft, a sleeve about the shaft extending between said bulk heads, means for attaching the canvas at one end of the bag to the shaft comprising a ring adapted to slide along said shaft, said sleeve being connected to said ring whereby gas is prevented from leaking from the interior of the bag 115 while the same is being inflated, said slideable ring permitting the spokes to fold along the shaft in a direction away from the end to which said ring is normally attached. 110

14. In an airship, the combination of a gas bag, a frame for holding the bag distended comprising a longitudinal shaft, a plurality of sets of radiating spokes pivoted to the shaft and secured at their outer ends to the canvas of the bag, said bag tapering at each end to the shaft and said spokes being adapted to fold along the shaft to allow for collapsing the bag, a ring to which the canvas at one end of the bag is secured, a transverse member at the end of the shaft 125

130

to which said ring may be clamped, a bulk head positioned on the shaft a short distance from one end thereof, a collapsible sleeve connecting said ring and said bulk head, and means for detachably securing said ring to the member at the end of the shaft.

15. In an airship, the combination of a gas bag, a frame for holding the bag distended comprising a shaft and a plurality of sets of radiating spokes pivoted to the shaft, means for securing said spokes at their outer ends to the canvas of the bag comprising a plate on the inner side of the canvas, inward projections on said plate adapted to embrace the end of the spoke, a spring member carried by the end of the spoke and having outwardly turned ends pivotally engaging said projections, said spring member being adapted to be collapsed to release the pivoted engagement.

16. In an airship, the combination of a gas bag, a frame for holding the bag distended comprising a shaft and a plurality of sets of radiating spokes pivoted to the shaft, means for securing said spokes at their outer ends to the canvas of the bag comprising a plate on the inner side of the canvas, inward projections on said plate adapted to embrace the end of the spoke, a spring member carried by the end of the spoke and having outwardly turned ends pivotally engaging said projections, said spring member being adapted to be collapsed to release the pivoted engagement, a clevis within said projections having its ends pivotally engaging the spring member, and brace wires secured to said clevis.

17. In an airship, the combination of a gas bag, a frame for holding the bag distended comprising a shaft and a plurality of sets of radiating spokes pivoted to the shaft, means for securing said spokes at their outer ends to the canvas of the bag comprising a plate on the inner side of the canvas, inward projections on said plate adapted to embrace the end of the spoke, a spring member carried by the end of the spoke and having outwardly turned ends pivotally engaging said projections, said spring member being adapted to be collapsed to release the pivoted engagement, a clevis within said projections having its ends pivotally engaging the spring member, and brace wires secured to said clevis, said spring member comprising a U-shaped wire having outwardly turned ends pivotally engaging the end of the spoke, the clevis and the projections, the intermediate portions of the U projecting outwardly from the spoke providing means for drawing the ends of the spring together.

18. In an airship, the combination of a gas bag, a frame for holding the bag distended comprising a longitudinal shaft, a series of

radiating spokes pivoted at their inner ends 65 to the shaft and means for securing the spokes at their outer ends to the canvas of the bag comprising a plate secured to the outer side of the canvas, a plate secured to the inner side of the canvas, means for clamping said plates together, the inner plate having inward projections embracing the inner end of the spoke, means for removably pivoting said projections to the end of the spoke, a net-work of wires extending 75 around the outside of the canvas, and projections on the outer plate for securing said wires thereto.

19. In an airship, the combination of a gas bag, a frame for holding the bag distended comprising a longitudinal shaft, a series of radiating spokes pivoted at their inner ends 80 to the shaft and means for securing the spokes at their outer ends to the canvas of the bag comprising a plate secured to the outer side of the canvas, a plate secured to the inner side of the canvas, means for clamping said plates together, the inner plate having inward projections embracing the inner end of the spoke, means for removably pivoting said projections to the end of the spoke, a net-work of wires extending 85 around the outside of the canvas, and projections on the outer plate for securing said wires thereto, washers extending over said 90 projections, and a pin extending there-through for holding the washer in position 95 outside the wires.

20. In an airship, the combination of a gas bag, a frame for holding the bag distended 100 comprising a longitudinal shaft, a plurality of sets of radiating spokes spaced apart and secured at their inner ends to the shaft and at their outer ends to the canvas, air compartments within the gas bag between the sets of spokes, and means connecting the compartments permitting the passage of air from one compartment to the other, said connection being between the spokes of a set.

21. In an airship, the combination of a gas bag, a frame for holding the bag distended comprising a shaft and outwardly extending members, said bag being made of canvas adapted to be wrapped around the frame and have its edges leading in a longitudinal seam and secured together, an inside air bag having its longitudinal wall secured to the canvas of the gas bag and extending about the shaft, transverse walls for said air bag 115 lying adjacent sets of outwardly extending members, said transverse walls also being arranged to permit the bag being folded over the balloon.

22. In an airship, the combination, with a 125 longitudinal shaft and a set of radiating spokes, of sectional bags located between the sets of spokes, and tubular connections be-

tween the bags, said connections being located at one side of the shaft and extending between the spokes of the set.

23. The combination of a gas bag, a frame 5 for holding the bag distended comprising a longitudinal shaft, a plurality of rings about said shaft, spokes pivoted to said rings and radiating therefrom and secured at

their outer ends to the bag, some of said spokes being of different lengths and some 10 of said rings being slid able along the shaft, said slid able rings permitting the spokes to fold along the shaft.

In testimony whereof, I hereunto affix my signature.

OSCAR J. LAISY.
